United States Patent Office

Des. 227,488
Patented June 26, 1973

227,488

GAME BOARD OR A SIMILAR ARTICLE

Samuel M. Spencer, 10147 Rustic Lane 45215, and James R. Davis, 8725 Hood Court 45231, both of Cincinnati, Ohio

Filed Apr. 21, 1972, Ser. No. 246,519

Term of patent 14 years

Int. Cl. D21—01

U.S. Cl. D34—5 SS

The figure is a plan view of the game board or a similar article embodying our new design.

The cross hatchings in the figure indicate contrasting colors.

The game board or a similar article is of conventional thickness.

We claim:

The ornamental design for a game board or a similar article, substantially as shown and described.
